(57) **CLAIM**

We claim the ornamental design for a computer pointing device, as shown and described.

DESCRIPTION

FIG. 1 is an isometric view of an embodiment of our design for a computer pointing device;

FIG. 2 is a front view of the design of the computer pointing device shown in FIG. 1;

FIG. 3 is a rear view of the design of the computer pointing device shown in FIG. 1;

FIG. 4 is a right side view of the design of the computer pointing device shown in FIG. 1, the left side view being a mirror image thereof;

FIG. 5 is a top view of the design of the computer pointing device shown in FIG. 1; and,

FIG. 6 is a bottom view of the design of the computer pointing device shown in FIG. 1.

The broken lines depict portions of the computer pointing device that form no part of the claimed design.

1 Claim, 6 Drawing Sheets
